United States Patent Office

Des. 232,430
Patented Aug. 20, 1974

232,430

HUB CAP

Henry James Clary, Orange, Calif.
(16427 S. Avalon Blvd., Gardena, Calif. 90248)

Filed May 24, 1973, Ser. No. 363,653

Term of patent 14 years

Int. Cl. D12—16

U.S. Cl. D12—204

Fig. 2.

FIG. 1 is a front elevational view of a hub cap showing my new design;

FIG. 2 is a cross sectional view thereof taken along the line 2—2 in FIG. 1;

FIG. 3 is a rear elevational view thereof; and

FIG. 4 is a side elevational view thereof.

I claim:

The ornamental design for a hub cap, as shown.
